SADDLE CONSTRUCTION

Roland W. Faulhaber, Monroeville, Ohio, assignor to The Faulhaber Company, Monroeville, Ohio, a corporation of Ohio

Application April 21, 1938, Serial No. 203,375

5 Claims. (Cl. 287—14)

This invention relates to saddles for cycles or the like and more particularly to an improved arrangement for mounting saddles upon children's tricycles or bicycles.

5 The principal object of this invention is to provide for both angular and sliding adjustment of saddles on a post or the like secured to the cycle. Other objects are to provide a mounting for saddles which is simple in construction and capable 10 of being economically manufactured, and to provide a single fastening means to clamp the saddle in both angularly and slidably adjusted position.

Further objects and advantages relating to 15 simplicity of construction and economy of manufacture will appear from the following detailed description and the appended drawing wherein:

Figure 1 is a side elevational view of a saddle embodying the post and reach connection of the 20 present invention,

Figure 2 is a sectional view taken on the line 2—2 of Figure 1, and

Figure 3 is a side elevational view of a saddle post made in accordance with this invention.

25 Referring to the drawing in which the preferred embodiment of my invention is illustrated, the numeral 10 indicates a saddle including a reach member 11, which in this embodiment comprises a flat piece of strap iron bent into a generally T-shape with the free ends 12 thereof terminating beneath the forward part of the seat portion 13. The return bends of the T-shaped reach are rounded as at 14 and, in the construction shown threadedly receive springs 15 and 16, the 30 upper extremities of which are secured to the seat portion 13 in any suitable manner. The free ends 12 of the reach are connected to the nose portion of the seat 13 by means of a member 17, which may be either resilient or rigid. The construction and arrangement of the springs may be 35 of any desired type. The specific construction of the reach member is not a part of the invention except as it enters into the combination with the mounting.

40 In the saddle mounting of the present invention the saddle post 20 is formed with a curved end portion 21 having outwardly extending opposed lugs 22. The body portion of the post is provided on each side with a plurality of opposed serrations or grooves 23 each of which is disposed on a 45 line intercepting the central axes of the lugs 22.

The central portion of the reach 11 is suitably apertured as at 24 to receive a clamping bolt 25. The reach portions between the rounded portions 50 14 and the apertures 24 are provided with elongated aligned slots 27 which, when the saddle is mounted upon the post 20, slidably receive the lugs 22 formed on the end of the arcuate portion 21 of the post. Similarly those portions of the reach between the apertures 24 and the free ends 12 are provided with opposed inwardly projecting ribs 28 which are adapted to seat within the serrations 23 formed on the body portion of the post 20. Each of the ribs 28 has a length equal to the length of the grooves or serrations 23 plus the 55 length of the slots 27.

In mounting the saddle 10 upon the post 20 the opposed portions of the reach 11 are spread apart a sufficient distance to permit the end of the post to pass therebetween and the lugs 22 to seat within the elongated slots 27. The reach is then pivoted about the lugs until the ribs 28 are seated within a pair of opposed serrations 23 which give the desired angularity to the seat portion 13. The seat is then placed in the desired slidably adjusted position by sliding the lugs 22 within the slots 27 and simultaneously sliding the selected serrations 23 along the ribs 28. The bolt 25 is then drawn up tight and the reach is rigidly secured to the post 20 in the desired slidably angular position.

5 In the foregoing invention I have provided a saddle in which the reach member thereof is connected to the post at spaced points, being slidably and pivotally connected at one of the points and having a slidably adjustable interengaging connection at the other point. The seat may be adjusted within a wide range to any desired seat angularity and likewise can be slidably adjusted through any necessary range toward and away from the handle bars. When the desired angular and fore and aft adjustment is reached the seat can be rigidly secured in position by a single bolt and at any time can be quickly and easily readjusted. It will be readily apparent that the foregoing construction is relatively simple and can be economically manufactured.

10 By the foregoing invention I have provided a saddle in which the reach member thereof is connected to the post at spaced points, being slidably and pivotally connected at one of the points and having a slidably adjustable interengaging connection at the other point. The seat may be adjusted within a wide range to any desired seat angularity and likewise can be slidably adjusted through any necessary range toward and away from the handle bars. When the desired angular and fore and aft adjustment is reached the seat can be rigidly secured in position by a single bolt and at any time can be quickly and easily readjusted. It will be readily apparent that the foregoing construction is relatively simple and can be economically manufactured.

15 While I have disclosed in detail the preferred embodiment of my invention it will be apparent that the invention may be embodied in various other constructions, and therefore I do not wish to be limited except as indicated in the following claims.

I claim:

20 1. The combination of a saddle post and a saddle having a reach member, said reach member being slidably and pivotally connected to said post at one point, and interengaging ribs and grooves on said post and reach extending radial- 25 ly of said pivotal connection and spaced there- 30

from for securing the reach to the post in adjusted position.

2. The combination of a saddle post and a saddle having reach members disposed on each side 5 of said post, said reach members being formed with elongated slots, extensions on the end of said post slidably engaging in said slots, and means for securing said reach members to said post in adjusted position.
- 10 3. The combination of a saddle post having an arcuate end portion and a saddle having reach members disposed on each side of said arcuate end portion, means for clamping said reach members to said post, said reach members engaging said 15 post at points oppositely spaced from said clamping means.

4. The combination of a saddle post having an arcuate end portion and a saddle having reach members disposed on each side of said arcuate

end portion, means for clamping said reach members to said post, said reach members being pivotally and slidably connected to said post on one side of said clamping means and interengaging means on said post and reach members on the 5 other side of said clamping means.

5. The combination of a saddle post having an arcuate end portion and a saddle having reach members disposed on each side of said arcuate end portion, said reach having elongated slots 10 adapted to receive oppositely extending lugs formed on the arcuate portion of said post, and opposed ribs formed on said reach members and spaced from said slots engaging with serrations formed on the opposite sides of said post, where- 15 by said reach members are pivotally and slidably connected to said post at one point and have an interengaging connection at another point.

ROLAND W. FAULHABER.
